UNITED STATES PATENT OFFICE.

ANDREW NILSON, OF CHICAGO, ILLINOIS, ASSIGNOR TO THE EUREKA SMOKELESS FURNACE COMPANY, OF CHICAGO, ILLINOIS, A CORPORATION OF ILLINOIS.

FURNACE.

1,221,082.

Specification of Letters Patent.

Patented Apr. 3, 1917.

Application filed February 14, 1916. Serial No. 73,089.

To all whom it may concern:

Be it known that I, ANDREW NILSON, a citizen of the United States, residing at Chicago, in the county of Cook and State of Illinois, have invented a certain new and useful Improvement in Furnaces, of which the following is a full, clear, concise, and exact description, reference being had to the accompanying drawings, forming a part of this specification.

My invention relates to furnaces and has for its object the provision of an improved structure thereof by virtue of which economies in coal consumption may be effected. My invention among other things concerns itself primarily with a suitable distribution of air and combustible gases, and concerns itself with their suitable intermixture.

Furnaces constructed in accordance with my invention are practically self-regulating or automatic in their nature, supplying the right amount of air to thoroughly combust the gases given off from the coal or fuel, thus preventing loss and at the same time almost entirely eliminating smoke; for practical purposes it may be said that the smoke is entirely eliminated.

My invention may be applied to furnaces for heating buildings or to furnaces of other characteristics, but in this present application I am describing a furnace used for heating purposes which is constructed in accordance with my invention. I will describe such a particular form which my invention may take in connection with the accompanying drawings, in which—

Figure 1 is a longitudinal sectional view of a furnace constructed in accordance with my invention;

Fig. 2 is a sectional view on line *a—a* of Fig. 1;

Fig. 3 is a sectional view on line *b—b* of Fig. 1;

Fig. 4 is a sectional view on line *c—c* of Fig. 2;

Fig. 5 is a sectional view on line *d—d* of Fig. 1, and

Fig. 6 is a detail perspective view of the arch or baffle wall support.

My furnace as here illustrated has the side walls 1 and 2, the upper arch 3 and the boiler portion 4. The furnace proper is divided into a fire box 5, and combustion chamber 6, which are separated by a baffle wall structure 7 which extends across the

full width of the furnace and extends downwardly to about the top of what would be the normal height of the coal or fuel 8, thus leaving an opening 9 under this baffle wall, which opening extends the full width of the furnace between the elements 10 and 11. This opening 9, as stated, is normally substantially closed by the fuel 8, the top of the fuel sloping downwardly immediately to the rear of this baffle wall as is most clearly shown in Fig. 1. The furnace is of course provided with any customary style of grate 12 and suitable grate operating handle 13 which permits the dumping of the ashes from the fire box into the ash pit or ash pan 14. A suitable door 15 permits access from the front to the ash pit and this door may of course be opened or closed in any regulatory manner as may be desired. The fire box is also provided with suitable doors 16 as is readily understood.

In addition to the baffle wall structure, which will be more clearly explained hereinafter, my novel furnace also includes means for supplying air to the front part of the fire box, which air may be suitably obtained from anywhere, but which in the particular construction herein shown is obtained from the ash pit, and thus in a measure helps the self-regulating qualities of the furnace. These means for supplying air to the front of the furnace consist of hood elements 17 which may rest upon the side member 18 of the grate and which at the top may rest against the side wall of the furnace, which in this case is the wall of the water leg 19, all as more clearly apparent from Fig. 5. These hood members 17 thus provide channels by which the air may come from the ash pit 14 (Fig. 5) into this channel formed by the elements 17 and thence through openings 20 into the fire box, all as shown by the arrows more clearly in Figs. 5, 1 and 2. It is thus seen that a fresh supply of air which is used to mix with the uncombusted gases driven from the coal is thus supplied to the furnace and by suitably intermingling assists to complete the combustion and to provide for a complete combustion of all of the particles so as to prevent smoking. This supply of air assists, for instance, in thoroughly combusting the thick volumes of uncombusted matter which rise from the coal immediately the furnace is fired or filled with a fresh supply of coal or fuel.

In addition, my invention has for one of its objects, as before stated, the construction of the baffle wall structure 7 which has been partly described in such a way that this 5 baffle wall structure includes a pair of channel elements 10 and 11, which, as shown more clearly in Fig. 3, rest upon the side bars 18 of the structure and thus provide a duct or channel from which air may pass from the 10 ash pit 14 (as shown by the arrows in Fig. 3) directly upwardly through said duct and into the hollow baffle wall structure. This hollow baffle wall structure is supported preferably by two pipes 21 and 22 which 15 extend preferably through the side walls of the furnace and which form supports for the front wall 23 and rear wall 24 of this hollow baffle wall structure. The channel elements 10 are provided with holes 25, 25 20 to accommodate the pipes 21 and 22, which pipes however, as readily apparent, are entirely inclosed serving merely as supporting elements. The space between the pipes 21 and 22 is left open as shown more clearly 25 in Figs. 1, 3 and 4 with the exception of a small portion leading inwardly from both sides, and which is closed by means of small brick portions 26, 26, thus to force the air passing upwardly through the elements 10 30 and 11 toward the center of the furnace structure as indicated more clearly by the arrows of Fig. 3, the fire being hotter in the center and needing more air than at the sides. The brick structure consisting of the 35 walls 23 and 24 is carried upwardly to the top wall of the furnace, thus closing it entirely at the top as is clearly apparent from Figs. 1 and 2, the top wall of the furnace proper being represented at 27.

40 Included in the hollow wall structure is a preferably metallic portion 28 which carries the doors 29 and 29 which may be used for cleaning purposes. This metallic structure also provides openings 30, 30 into which the 45 mixture from the fire box may enter and pass downwardly into the interior 31 of the hollow arch, as shown more clearly by the arrows in Figs. 1, 2, 3 and 4. An enlarged opening 32 is provided as shown more 50 clearly in Figs. 3 and 4 to assist in the passage of the mixture into the interior of the hollow arch. The mixture from the fire box may then pass into the hollow arch and out through the bottom thereof, as shown more 55 clearly by the arrows of Fig. 4, and from there pass into the combustion chamber where the heat is intense and where these uncombusted gases and mixtures burn in a manner to provide complete combustion.

60 Additional air is of course supplied also to the interior of the hollow arch, this air passing upwardly through the ducts 10 and 11. As before stated, the air which passes through the ducts 10, 11 and 17 is taken from 65 the ash pit. Furthermore the fuel does not

entirely cover the entire surface of the grate which forms the lower wall of the combustion chamber 6, and thus additional air passes upwardly from the ash pit into the combustion chamber.

70

From what has been described the nature of my invention will be readily clear to those skilled in the art. Having however thus described one form which my invention may take, what I claim as new and desire 75 to secure by Letters Patent is:

1. A furnace structure having a fire box, combustion chamber and ash pit, a baffle wall structure interposed between said combustion chamber and fire box, a grate underneath both fire box and combustion chamber, said baffle wall having openings to permit the passage of gases from the fire box to the combustion chamber, means for supplying fresh air for mixing with the gases immediately to the rear of said openings, and means for supplying fresh air to the front portion only of said fire box above the grate.

80

85

2. A furnace structure having a fire box, combustion chamber and ash pit, a baffle wall structure interposed between said combustion chamber and fire box, a grate underneath both fire box and combustion chamber, said baffle wall having openings to permit the passage of gases from the fire box to the combustion chamber, means for supplying fresh air for mixing with the gases immediately to the rear of said openings, and means for supplying fresh air to the front portion only of said fire box above the grate,

90

95

100

both of said means communicating with said ash pit.

3. A furnace structure having a fire box, combustion chamber and ash pit, a baffle wall structure interposed between said combustion chamber and fire box and extending downwardly to the normal top level of the fuel, a grate underneath both fire box and combustion chamber, said baffle wall having openings to permit the passage of gases from the fire box to the combustion chamber, means for supplying fresh air for mixing with the gases immediately to the rear of said openings, and means for supplying fresh air to the front portion only of said fire box above the grate.

105

110

115

4. A furnace structure having a fire box, combustion chamber and ash pit, a baffle wall structure interposed between said combustion chamber and fire box and extending downwardly to the normal top level of the fuel, said baffle wall having openings to permit the passage of gases from the fire box to the combustion chamber, means for supplying fresh air for mixing with the gases immediately to the rear of said openings, and means for supplying fresh air to the front portion only of said fire box above the grate.

120

125

5. A furnace structure having a fire box, combustion chamber and ash pit, a baffle wall structure interposed between said combustion chamber and fire box and extending downwardly to the normal top level of the fuel, said baffle wall having openings to permit the passage of gases from the fire box to the combustion chamber, means for supplying fresh air for mixing with the gases immediately to the rear of said openings, and means for supplying fresh air to the front portion only of said fire box above the grate, both of said means communicating with said ash pit.

130

5. A furnace structure having a fire box, combustion chamber and ash pit, a hollow baffle wall structure interposed between said combustion chamber and fire box and extending downwardly approximately to the normal top level of the fuel, said baffle wall having openings leading from said fire box into its hollow interior, means for supplying air to the interior of said baffle wall, means for directing the mixture from the interior of said baffle wall into the combustion chamber, and means for supplying air to the front portion only of said fire box above the grate, both of said air supplying means communicating with said ash pit. 35
- 10 6. A furnace structure having a fire box, combustion chamber and ash pit, a grate underneath both fire box and combustion chamber, a hollow baffle wall structure interposed between said combustion chamber and fire box, said baffle wall having openings leading from said fire box into its hollow interior, means for supplying air to the interior of said baffle wall, means for directing the mixture from the interior of said baffle wall into the combustion chamber, and means for supplying air to the front portion only of said fire box above the grate. 40
- 15 7. A furnace structure having a fire box, combustion chamber and ash pit, a grate underneath both fire box and combustion chamber, a hollow baffle wall structure interposed between said combustion chamber and fire box, said baffle wall having openings leading from said fire box into its hollow interior, means for supplying air to the interior of said baffle wall, means for directing the mixture from the interior of said baffle wall into the combustion chamber, and means for supplying air to the front portion only of said fire box above the grate. 45
- 20 8. A furnace structure having a fire box, combustion chamber and ash pit, a baffle wall structure interposed between said combustion chamber and fire box, a grate underneath both fire box and combustion chamber, said baffle wall having openings to permit the passage of gases from the fire box to the combustion chamber, means for supplying fresh air for mixing with the gases immediately to the rear of said openings, and means for supplying fresh air to the front portion only of said fire box above the grate, said last aforesaid means consisting of a hollow element extending upwardly from said grate at the front portion of said fire box, and having holes through its side wall leading from the interior of said element to said fire box. 50
- 25 9. A furnace structure having a fire box, combustion chamber and ash pit, a grate underneath both fire box and combustion chamber, a hollow baffle wall structure interposed between said combustion chamber and fire box, said baffle wall having openings leading from said fire box into its hollow interior, means for supplying air to the interior of said baffle wall, means for directing the mixture from the interior of said baffle wall into the combustion chamber, and means for supplying air to the front portion only of said fire box above the grate. 55
- 30 10. A furnace structure having a fire box, combustion chamber and ash pit, a grate underneath both fire box and combustion chamber, a hollow baffle wall structure interposed between said combustion chamber and fire box, said baffle wall having openings leading from said fire box into its hollow interior, means for supplying air to the interior of said baffle wall, means for directing the mixture from the interior of said baffle wall into the combustion chamber, and means for supplying air to the front portion only of said fire box above the grate. 60

In witness whereof, I hereunto subscribe my name this 10th day of February, A. D. 1916.
